UNITED STATES PATENT OFFICE.

HENRY P. SCHOENKY, OF ST. LOUIS, MISSOURI, ASSIGNOR TO AMERICAN SHOE MACHINERY & TOOL COMPANY, OF ST. LOUIS, MISSOURI, A CORPORATION OF MISSOURI.

WAX-THREAD SEWING-MACHINE.

1,242,606.

Specification of Letters Patent.

Patented Oct. 9, 1917.

Application filed January 10, 1916. Serial No. 71,179.

To all whom it may concern:

Be it known that I, HENRY P. SCHOENKY, a citizen of the United States, and a resident of the city of St. Louis and State of Missouri, have invented a new and useful Improvement in Wax-Thread Sewing-Machines, of which the following is a specification.

This invention relates to leather sewing machines of the lock stitch type, and is intended particularly for use in shoe repair shops for sewing on outsoles, but the invention is not restricted to such stitching machines.

The objects of the invention are simplicity of construction, strength and durability, together with ease of operation and adjustment for all classes of work, such as to make a practical stitching machine for use by ordinary shoe workers without the attention of skilled operators or machinists. Further objects of the invention appear hereinafter.

The invention consists in the form and in the arrangement of the various parts of the machine so as to produce a uniform stitch regardless of irregularities in the thickness or character of the work. The invention further consists in the arrangement of the parts for convenient operation of the machine, and for easy inspection and adjustment or repair, as hereinafter described. What the invention consists in is further set forth in the appended claims.

A machine embodying the invention in an operative form is shown in the accompanying drawings forming part of this specification. The same reference characters are used throughout the several views of the drawings to designate the same parts of the machine.

Referring to the drawings,

Figure 1 is a front elevation of a machine embodying the invention;

Fig. 2 is a side view of the right hand side of the machine, the driving wheel and a part of the frame being removed to disclose the operating parts;

Fig. 3 is a side view of the left hand side of the machine, the frame being partly removed;

Fig. 4 is a rear elevation of the machine;

Fig. 5 is a vertical section through the

machine on the line 5—5 in Fig. 3, looking at it from the front;

Fig. 6 is a horizontal section through the machine on the line 6—6 in Fig. 3, looking down, showing the work table and feeding mechanism and looper actuating mechanism in plan;

Fig. 7 is a vertical section through a portion of the machine on the line 7—7 in Fig. 6, looking in the direction of the arrows;

Figs. 8 and 9 are a plan view and a front view, respectively, of the stitch-forming mechanism in the operation of forming a stitch, the work being removed and the work table being broken away in the plan view to disclose the parts beneath, showing the position of the parts at the beginning of the formation of the loop in the needle thread, the main cam having rotated through 230° from its zero position;

Figs. 10 and 11 are similar views to Figs. 8 and 9, showing the parts after the looper has pulled the loop open and the shuttle has picked it up, the main cam having rotated through 275°.

Figs. 12 and 13 are similar views, showing the parts after the looper has cast off the loop and the shuttle has oscillated far enough to carry the loop around the bobbin thread, the main cam having rotated through 305°;

Figs. 14 and 15 are similar views, showing the parts after the shuttle has completed its loop carrying movement and has cast off the loop, and after the take-up has started to pull the stitch tight, the main cam having rotated through 330°;

Figs. 16 to 18, inclusive, are detail views of the awl holder and channeling knife, Fig. 16 being a front view, and Fig. 17 being a vertical section and Fig. 18 a horizontal section on the axis of the holder;

Fig. 19 is a detail view of the holding bolt for the awl removed from the other parts;

Fig. 20 is a sectional view of two pieces of leather sewed together, showing the stitch formed by the machine; and

Fig. 21 is a diagram illustrating the sequence of operation of the various parts of the machine, and the time intervals between the various movements.

General description of the machine.

The machine shown in the drawings has a main frame consisting of a base 10, side walls 11 and a front wall 12. Projecting forward from the front wall is a table 13 for supporting the work being sewed, and an arm 14 for supporting the presser foot and needle bar. The front end of the arm 14 is covered by a plate 15 which is provided with a chamber for heating it by steam. A steam chamber 16 surrounds the recess 17 below the work table for the shuttle and bobbin. Steam is circulated through the steam chambers by means of pipes 18. The work table has a slot 19 through it parallel to its front edge for the awl and needle to work through. The work is held by the operator with its top side up, and is guided by hand.

20 The work is fed forward for each stitch by the awl 20, which operates from below the work table in front of the shuttle. The awl is carried by a vertically and sidewise movable holder 21, which also carries a channel cutter 22 for grooving the underside of the work to form a channel for the thread. The work is held in place on the table by a presser foot 32 which operates from above the table.

There are two threads used in forming the stitch, the top thread 40 being led through the eye of the needle 41 which operates from above the work, and the bottom thread 50 being supplied from a bobbin 51 which is carried by the shuttle 52 which operates below the work table. The stitch forming mechanism comprises also a looper 60, which operates below the table in connection with the shuttle, and a take-up lever 70 which cooperates with the needle for measuring the 40 length of top thread required for each stitch, and for pulling both threads tight at the completion of the stitch. The top thread is locked by a thread clamp 75, which is released during the thread measuring movement of the take-up lever. The needle and awl are both straight, but the invention is not restricted to a straight needle and a straight awl.

The awl, feeding mechanism, presser foot, 50 needle, shuttle, looper, take-up device and thread lock are all operated from a rotating cam disk 80 mounted on the main shaft 81 of the machine. The main shaft 81 is horizontally journaled in bearings 82 in the side walls 11 of the machine frame, and has a hand wheel 83 on its right hand end. The main shaft is driven from a suitable source of power, such as a foot pedal and crank or a small electric motor, by means of a belt 55 running in a groove 84 in the hand wheel.

A wax pot 66 is provided for waxing the 60 thread. The wax pot is located on top of the frame of the machine at the back, and is steam jacketed for keeping it hot. The 65 thread is led to the wax pot from any suit-

able source of supply, such as a spool not shown in the drawings.

Awl and channel cutter.

The awl 20 is adjustably secured to the 70 awl holder 21 by means of a clamping bolt 201 which has a hole through it under its head for the awl, and a pin 202 on the inner side of the head in line with the hole for the end of the awl to rest on. The clamping 75 bolt goes through a transverse hole 203 through the upper end of the awl holder from back to front, and has a square shoulder 204 on the inner side of its head which engages in a horizontal groove 205 on the 80 back side of the holder. The hole 203 is slot shaped, with its long axis vertical, and an eccentric 206 is arranged on the clamping bolt partly in the slotted hole, the diameter of the eccentric portion just filling the width 85 of the hole. The eccentric has a flange which bears against the front of the awl holder around the hole. By rotating the eccentric, the clamping bolt is adjusted horizontally 90 toward one side or the other of the machine. The awl, clamping bolt and eccentric are secured in adjusted position by screwing up the nut 207 on the front end of the clamping bolt.

The channel cutter 22 comprises a plate 95 carrying a pair of knives or chisels 221 which are arranged one on each side of the awl. The upper edges of the knives cut into the under side of the work at the top of the upward movement of the awl holder, thereby forming a shallow groove connecting the awl holes on the under side of the work. The slot 19 in the work table is long enough to permit the channeling knives to operate through it. The channel cutter 22 rests on the top of the awl holder and has a flange 222 which hangs over the front edge of the awl holder and is clamped to the eccentric and awl holder by the clamping nut 207. Hence, the channel cutter is adjustable 100 with the awl lengthwise on the awl holder. 110

Awl-feeding mechanism.

The awl holder 21 is mounted to slide 115 horizontally from side to side in a slide box 23, which in turn is slidably arranged for movement up and down in ways 231 on a forwardly projecting portion of the front wall 12 of the machine frame below and to the side of the work table 13. The ways are provided with gib 234 which can be adjusted to take up wear in the slide box and ways by means of screws 235. The slide box has a horizontal slot in its front side 120 for the awl holder to slide in, and this slot is covered by a removable front plate. The slot has a gib 232 which may be adjusted by screws 233 to take up wear in the slide 125 21 and walls of the slot. 130

The awl holder 21 extends through the slide box 23 and has a vertical groove 210 on the inner side of its projecting end. This grooved end of the awl holder slides in front of the end of an oscillating shaft 24, and when the awl is in alignment with the needle the center of the groove 210 intersects the axis of the oscillating shaft. This oscillating shaft 24 has a sector 240 on its front end with a groove 241 in its front face intersecting the axis of the shaft. This groove 241 stands vertically in one extreme position of oscillation of the shaft 24, and it makes an angle of about forty-five degrees with the vertical in its other extreme position. An adjusting arm 25 is pivoted eccentrically to the front of the sector 240, and may be clamped in angularly adjusted position on said sector by the thumb nut 250 and J-20 clamp bolt 251 which engages under the outer edge of the sector. The adjusting arm has a slot through it extending crosswise in front of the groove 241 on the sector, and a stud 252 is mounted in the slot in the adjusting arm with its inner end projecting into the sector groove and fitted to slide therein toward or away from the axis of the oscillating shaft 24 when the adjusting arm is angularly adjusted on the sector. The stud has a shoulder against which the inner face of the adjusting arm bears to clamp the stud in the groove. The outer end of the stud 252 has a roller 254 secured on it which engages in the groove 210 in the awl holder. The sector 240 has a scale marked on its outer edge for setting the adjusting arm 25 to position the stud in the groove 241 at the proper distance from the axis of the oscillating shaft 24 for sliding 40 the awl holder whatever distance is desired for the length of the stitch.

The oscillating shaft 24 is movable axially in its bearings toward the back of the machine to withdraw the sector, stud and roller 45 from the groove 210 in the awl holder. A spring 242 normally holds the shaft and parts carried thereby in forward position. By pushing the sector 240 back, the awl holder may be freed from the roller 254 and shifted sidewise far enough to carry the awl end away from in front of the shuttle, in order that the bobbin may be conveniently removed and replaced. The oscillating shaft has a crank 243 on its back 50 end to which one end of a connecting rod 26 is pivoted. The other end of the connecting rod is pivoted to the lower end of an oscillating lever 27 which is pivotally mounted at its middle on a bearing on the back of 55 the front wall of the frame. The pivotal axis of the lever 27 is parallel to that of the oscillating shaft 24. The upper end of the lever 27 carries a cam roll 270 which engages in a cam groove 28 on the periphery 60 of the cam disk to cause the lever 27 and

shaft 24 to oscillate back and forth at the proper time to feed the work, as hereinafter described.

The slide box 23 is moved up and down by means of a bell crank lever 29 to which it is connected by a link 30. The bell crank lever is pivotally mounted in bearings at the bottom of the machine frame parallel to the cam shaft and at one side of the cam 80. The rear end of the bell crank lever 29 carries a roller 291 which co-operates with a cam groove 31 in the face of the cam 80 to swing the bell crank lever and raise and lower the slide box for the awl holder, and to hold it motionless in either position. The shape of the cam groove 31 is such that the awl is raised to penetrate the work, is held up until the feeding device has moved the awl into vertical alignment with the needle, and is withdrawn in advance of the downward movement of the needle.

Presser foot mechanism.

The presser foot 32 is mounted on the lower end of a square slide bar 33 which is guided for up and down movement in a suitable slot in the front of the arm 14 behind the steam chamber plate 15. The toe of the presser foot rests upon the work over the work table, and is provided with a slot 34 through it in vertical alignment with the slot 19 in the work table. The presser foot is held down by a clamp bar 35 which co-operates with a cam operated rocker arm or lever 36. The clamp bar has a square hole 100 in it near its front end through which the square slide bar 33 passes loosely. The clamp bar is supported at its front end by means of a spring 331 which is mounted on a rod 332 which projects down from a lug 105 150 on the under side of the front plate 15 on the arm 14 of the machine. The rod 332 passes loosely through a hole in the front end of the clamp bar, and carries a stop 333 above the end of the clamp bar against 110 which the latter is pressed by the spring to hold it horizontal and free of the slide bar when the clamping lever is not held down at its back end by the rocker arm or lever 36.

The rocker lever 36 is pivoted at its 115 middle to oscillate in a vertical plane behind the presser foot slide bar. A roller 361 on the front end of the rocker lever bears on the back end of the clamp bar; and the back end of the rocker lever has a roller 362 120 which rolls on one edge of the periphery of the cam disk 80 to hold it up and thereby clamp the presser foot down. The presser foot is free to lift vertically through the hole in the clamp bar when the latter is 125 horizontal, and at such times the work may be fed by the awl and positioned or guided by the operator. The presser foot is automatically released during the period of feeding the work by the awl by a suitable 130

notch 37 in the edge of the cam disk; and a second short notch 38 permits the release of the clamp at the end of the stitch for the purpose of shifting the work if desired.

- 5 A hand lever 39 for lifting the presser foot by hand is pivoted to a lug 150 on the front plate 15 of the arm 14, which projects down alongside of the slide bar 33 above the clamp bar. The hand lever has an arm 390 which is provided with a cam slot 391 in which a pin 392 on the slide bar works. A light spring 393 holds the hand lever and presser foot down. The hand lever can be operated conveniently only when the roller 15 362 is in one of the cam notches 37 or 38, although the front end of the clamp bar may be depressed by means of a suitable tool to release the slide bar regardless of the position of the cam.

20 *Needle and shuttle actuating mechanism.*

- The needle 41 is clamped to a block 42 upon the lower end of the needle bar 43 by means of a clamping nut 421 which screws on a stud 422 in the front of the block 42. The shank end of the needle goes through a hole in the clamping stud and bears against a pin which is fixed in the clamping block, and a washer 423 is arranged on 30 the stud between the clamping nut and the needle to hold the latter in place. The needle bar 43 slides vertically up and down in a suitable slot in the arm 14 of the machine behind the front plate 15. An adjustable gib 44 is provided for taking up wear in the needle bar and guide slot.

- The needle bar is raised and lowered at the proper times for making the stitch by means of a series of links and swinging 40 arms and levers actuated from the main cam 80. A link 45 is connected at one end to the needle bar and at the other end to the front end of a horizontal rocker arm 46 which is pivoted near its middle on the 45 shaft 73 to oscillate in a vertical plane. The back end of the rocker arm is connected by means of a link 47 to a swinging lever 48 which is pivoted at one end to the back of the frame of the machine. The swinging 50 lever carries a cam roll 481 which co-operates with the cam groove 49 in the face of the cam.

- The lower thread 50 is wound on a bobbin or spool 51 which is carried by a stationary 55 bobbin case 53 mounted loosely in the shuttle 52. An arm 54 pivoted on the front of the frame under the work table engages a stud 531 on the bobbin case to hold it stationary. This arm can be thrown out of the 60 way when it is desired to remove the bobbin. The shuttle 52 is loosely mounted in an annular recess 171 in the frame under the work table, and is held in place by means of a removable ring 172. The shuttle is oscillated by means of a driver arm 55 which

loosely engages a notch in its periphery in front of the point of the shuttle. The driver arm 55 is fixed on the front end of the horizontal shaft 56 which is journaled in the frame under the work table and which has 70 a spur gear 57 upon its back end engaging with a rack upon a vertical sliding bar 58 which is mounted in a vertical guide slot in the frame back of its front wall. The rack bar is connected by means of a link 59 with the front end of the swinging lever 48 which 75 operates the needle bar. Upward movement of the front end of the swinging lever 48 causes the needle bar to lower and simultaneously oscillates the shuttle in the same direction as the hands of a clock, and vice versa.

Looper mechanism.

The looper 60 slides forward and back in 85 a recess below the work table, its path of movement passing close to the left side of the path of movement of the needle. The looper is attached to a horizontal rod 61 which is slidably arranged in the frame 90 below the table. The looper rod is operated from the cam disk 80 by means of a link 62 which connects its back end with the upper end of a swinging lever 63. The swinging lever 63 is pivoted at its lower end to a fixed 95 bearing upon the side wall of the frame of the machine. This swinging lever 63 carries a cam roll 631 which engages with a cam groove 64 in the face of the cam disk 80. The cam groove 64 for operating the 100 looper is so shaped as to cause the looper to move forward to pass the needle after the latter has penetrated the work, and to withdraw it immediately. The front end of the looper is provided with a hook which 105 catches the needle thread and pulls it back in the form of a loop into the recess under the work table and in front of the point or hook on the periphery of the shuttle 42. Immediately after the shuttle starts to rotate to pick up the loop of thread, the looper moves forward again a short distance to disengage its hook from the loop of needle thread, and the shuttle hook carries the thread loop off of the looper hook and on 110 to a finger 65 which projects from the side wall of the recess alongside of the path of movement of the shuttle in line with the axis of the looper.

Wax pot and thread guides.

120

The thread 40 is led to the needle from the wax pot 66 over a pair of fixed rollers 67 arranged one above the other upon an arm 151 which projects up from the plate 125 15 on the front of the arm 14 of the machine. The thread is led through the wax pot from bottom to top between oppositely arranged guides 661 which screw into threaded openings in the walls. Rubber 130

disks 662 having center holes for the thread are squeezed between the guides and bottoms of the openings in the walls to strip the wax from the thread. A loop of the needle thread is passed back from the top roller 67 around a roller 69 on the end of the take-up lever 70, the thread passing forward from the roller 69 to the lower fixed roller 67 upon the front of the machine. From 10 the lower roller the thread leads across the heated front plate 15 of the arm and under a light spring 68 at the lower edge of the arm.

Take-up mechanism.

15 The take-up lever 70 is pivoted upon the arm 14 back of the guides for the presser foot and needle bar, and is operated from the cam disk 80. A connecting link 71 is 20 pivoted at one end to the take-up lever and at the other end to the front end of a crank lever 72 having two lever arms securely keyed on a horizontal shaft 73. The rear arm 721 of the crank lever carries a cam 25 roll 722 at its end which engages in a groove 74 on the face of the cam disk 80. The shaft 73 thus forms a portion of the crank lever 72, and is journaled at its ends in fixed bearings in the frame of the machine. The 30 middle portion of the shaft 73 supports the rocker arm 36 for clamping the presser foot, and this shaft also supports the lever 46 which operates the needle bar.

A thread clamp 75 is provided upon the 35 back of the machine for clamping the thread before it enters the wax pot. The thread clamp consists of a vertically movable clamping pin carrying a disk 751 at its lower end which clamps the thread against the lower face of the lug 76 on the lower 40 edge of the wax pot. The clamping disk is held lightly against the thread at all times by means of a spring 752 which rests upon the lug 76 and bears against an adjustable 45 nut 753 on the threaded stem of the thread clamp 75. The clamping disk is held in clamping position by means of the clamping lever 77 which is pivotally mounted at one end beneath the wax pot, and which carries 50 a roller 771 at its other end for co-operating with one edge portion of the periphery of the cam disk 80. The clamping lever has an adjustable thumb screw 772 which is adapted to bear against the lower face of 55 the clamping disk and press it against the thread. The screw is held in adjusted position by means of a lock nut 773. The cam disk has two notches in its periphery, and when the roller 771 drops into one or the 60 other of these notches the pressure of the clamping lever against the clamping disk is relieved. One notch 78 is suitably located upon the cam disk to open the thread lock when the take-up lever is measuring thread. 65 The other notch 79 is located upon the cam

in line with the notch 38 which relieves the pressure on the presser foot upon completion of the stitch, for the purpose of enabling the work to be manipulated by the operator.

70

Operation of the machine.

Fig. 21 shows diagrammatically the order in which the various parts of the machine operate, and the relative positions of the 75 working parts at every stage in the formation of a stitch. By turning the hand wheel 83 so as to bring the cam notches 38 and 79 under the rollers 362 and 771 on the levers 36 and 77 which operate the 80 presser foot clamp and thread lock, respectively, the presser foot is released and the thread lock is opened, and the work can be brought in position on the work table under the presser foot, and a short length of 85 thread pulled through the eye of the needle. A slight movement of the top of the hand wheel away from the operator clamps the presser foot down on the work and closes the thread lock, and the machine is ready 90 for operation by power. The cam is rotated in the direction of the arrows in Figs. 2 and 3, and the shapes of the various cam grooves and shapes and arrangement of the levers and links are such as to produce 95 synchronous movement of the operating parts as follows:

First, the awl moves up through the work, moves sidewise toward the left to feed the work under the needle, and then withdraws 100 down through the work and moves back toward the right to its initial position out of the way of the needle. During the side-wise movement of the awl to feed the work the presser foot is released.

105

The needle moves down simultaneously with the withdrawal of the awl, and carries the top thread through the work and below the path of movement of the looper, and as the looper moves forward the needle rises 110 slightly to form a loop of thread for the looper to pass through. During the downward movement of the needle the shuttle is turning in the same direction as the hands of a clock to bring its point in readiness 115 to pick up the loop.

The needle and shuttle rest while the looper is completing its forward movement; and during the latter part of the forward movement of the looper, the parts being in 120 the positions shown in Figs. 8 and 9, the take-up lever moves away from the front of the arm 14 to measure thread for the stitch, the thread lock being open during this movement. The resistance of the 125 thread to movement through the thread clamp and wax pot causes all the slack to be taken out of the thread and the loop around the looper to be pulled tight, so that the take-up pulls a variable length of thread 130

through the thread lock substantially equal to whatever length may be needed for the stitch. The length of thread between the thread clamp and needle is considerable and it will stretch more or less, depending on the tension of the spring 752, thereby diminishing or increasing the amount of thread pulled through the thread lock for a certain length of stitch. Hence, the length of thread pulled through for the stitch can be slightly increased or diminished, by adjusting the tension of the thread clamp spring 752, and thereby the tightness of the needle thread and stitch can be regulated. For sewing thick leather the tension of the spring 752 may be increased, and for thin leather it may be slackened.

Following the thread measuring movement, the thread lock 75 closes and the take-up lever 70 moves forward to pay out thread. The looper 60 simultaneously moves back, pulling a loop of thread with it across the path of movement of the point of the shuttle 52. During the last portion of the backward movement of the looper the needle starts to rise, and the shuttle starts to rotate anti-clockwise, so that when the looper reaches its extreme rear position the shuttle point has fully entered the loop, as shown in Figs. 10 and 11. The looper then moves forward a short distance to free the loop from its hook end, and the continuing rotation of the shuttle pulls the loop off the looper and over the finger 65 and carries it down behind the bottom thread 50, as shown in Figs. 12 and 13. The bottom thread is held in the stationary bobbin case 53, and is under tension, produced by a spring in the bobbin case, to keep it taut. During this movement of the shuttle the take-up lever moves forward to pay out enough excess thread, which is pulled through the eye of the needle by the shuttle, to permit the loop to pass around the shuttle and bobbin case. The looper then goes back to its rear position out of the way of the loop, and remains at rest during the remainder of the stitch forming operation, and the shuttle continues its rotation in an anti-clockwise direction until it has nearly reached its starting point, as shown in Figs. 14 and 15. During the last portion of the rotation of the shuttle the take-up lever moves back to take up slack in the top thread 40 and pull the loop off the shuttle and around the bobbin through the space between the shuttle and driver arm 55.

The effect of the arrangement of looper and shuttle is to throw a twisted loop of the top thread around the bottom thread, as shown in Fig. 15. The take-up lever continues to pull in slack, until all the excess thread measured for the loop is taken up and the loop is pulled up into the work, carrying a bight of the bottom thread with it.

The act of pulling the top thread into the needle hole untwists the loop and puts a twist in the bight of the bottom thread, completing the stitch, as shown in Fig. 20. The extent to which the bottom thread is pulled into the needle hole is determined by the tension on the top thread and consequent stretch in the top thread during the thread measuring operation.

Upon finishing the sewing, the hand wheel is turned to bring the notches 38 and 79 in the cam 80 under the rollers which coöperate therewith, thereby releasing the presser foot and opening the thread lock to permit the work to be removed from the work table.

From the foregoing description it is apparent that the stitch forming mechanism is adapted to operate upon work of different character and thickness, and can be adjusted to form stitches of different length, as may be desired. The stitches are pulled uniformly tight regardless of their length and of the thickness of the work, and the tension may be adjusted to suit the character of the work. The presser foot positively clamps all thicknesses of work with the same pressure without requiring any adjustment, and it and the thread lock are automatically released at the completion of the stitching operation to permit removing the work from the table. The bobbin is easily removed and replaced without readjusting any of the parts; and the length of stitch may be adjusted without readjusting the thread tension. The thread measuring device is simple and not subject to derangement; and there are no small parts exposed to possible injury except the needle and awl, which are readily replaced. The form of the stitch is well suited to sewing on soles, as the twisted bight of the bottom thread will continue to lock the top thread after the portion of the thread in the channel is worn through.

The invention is not restricted to the details of construction shown and described, as it is evident that they are susceptible of modification.

I claim the following as my invention:

1. A sewing machine comprising a needle and shuttle operating on opposite sides of the work, a stationary bobbin carried by the shuttle, a looper, a thread lock, a take-up device between the thread lock and looper, and means to operate the needle, shuttle, looper thread lock and take-up device to throw a twisted loop of needle thread around the bobbin thread and pulling it tight to complete the stitch, whereby a twisted bight of bobbin thread is pulled into the stitch to lock the needle thread.

2. A sewing machine comprising a needle and shuttle operating on opposite sides of the work, a stationary bobbin carried by the shuttle, a looper, a thread lock, a take-up device between the thread lock and looper,

and means to operate the needle, shuttle, looper thread lock and take-up device to throw a loop of needle thread around behind the bobbin thread in a direction opposite to that in which the stitches are being formed, whereby a twisted bight of bobbin thread is pulled into the stitch to lock the needle thread.

3. A sewing machine comprising a work table, a needle bar operating from one side of said work table, a shuttle operating on the opposite side of said work table, a shaft for operating said shuttle and arranged for oscillation therewith, means for operating said needle bar and shuttle in synchronism comprising a cam, a swinging lever coöperating with said cam to follow its movements, a rocker arm arranged to reciprocate said needle bar, a link connection from said lever to said rocker arm, and a rack and pinion connection from said swinging lever to said oscillating shaft for oscillating said shuttle.

4. A sewing machine comprising a work table, a needle bar operating from one side of said work table, a shuttle operating on the opposite side of said work table, a looper, means for reciprocating said looper and for operating said needle bar and shuttle in synchronism comprising a cam having two grooves, a rocker arm arranged to reciprocate said needle bar, a swinging lever coöperating with said cam to follow one of said grooves, a link connection from said lever to said rocker arm, an oscillating shaft arranged to oscillate said shuttle, and a rack and pinion connection from said swinging lever to said oscillating shaft, and a second lever coöperating with said cam to follow the other groove, said second lever having a link connection with said looper.

5. A sewing machine comprising a work table and an eye-pointed needle operating from one side of said work table, a shuttle and a looper operating upon the opposite side of said work table, the path of movement of said looper passing between the thread and needle when the needle is through the work, a hook on said looper adapted to spread open a loop of needle thread, a fixed hook spaced from said work table in the path of movement of said looper, and a hook on said shuttle adapted to pick up the loop on said looper hook and pull it around said fixed hook.

6. A sewing machine comprising a work table and an eye-pointed needle operating from one side of said work table, a shuttle operating upon the opposite side of said work table, a fixed hook for holding the needle thread, said fixed hook being spaced from said work table, and a hook on said shuttle adapted to pick up a loop of needle thread and pull it around said fixed hook, and a stationary bobbin holder carried by said shuttle, the movement of said shuttle

around said bobbin holder throwing said loop around the bobbin thread.

7. A sewing machine comprising a work table and an eye-pointed needle operating from one side of said work table, a shuttle operating upon the opposite side of said work table, a fixed hook for holding the needle thread, said fixed hook being spaced from said work table, and a hook on said shuttle adapted to pick up a loop of needle thread and pull it onto said fixed hook, and a stationary bobbin holder carried by said shuttle, the movement of said shuttle around said bobbin holder twisting said loop around the bobbin thread, and a take-up device for pulling in the needle thread to pick up a twisted bight of bobbin thread.

8. A lock stitch sewing machine comprising a work table, a needle for carrying the top thread through the work, a looper for picking up said thread on the opposite side of the work to that on which the top thread lies and holding it momentarily, means for holding the lower locking thread for passage of the needle thread loop around the same, and a take-up device having an initial movement for pulling the loop taut against the looper while in the needle loop, said take-up device having a further movement for pulling thread from the thread supply.

9. A lock stitch sewing machine comprising a work table, a needle for carrying the top thread through the work, a looper for picking up said thread on the opposite side of the work to that on which the top thread lies and holding it momentarily, means for holding the lower locking thread for passage of the needle thread loop around the same, and a take-up device having an initial movement for pulling the loop taut against the looper while in the needle loop, said take-up device having a further movement for pulling thread from the thread supply, and a thread lock between said take-up device and thread supply.

10. A sewing machine comprising a work table, a needle for forming a loop of the top thread beneath the work, a looper for picking up said thread on the opposite side of the work to that on which the top thread lies, and a take-up device having an initial movement for pulling the loop taut against the looper while in the needle loop, said take-up device having a further movement for pulling thread from the thread supply, and a thread lock between said take-up device and thread supply, said thread lock being at a distance from the looper and having an adjustable tension device for maintaining a greater or less tension on said top thread during the movement of said take-up device for pulling thread from the supply.

11. A sewing machine having a needle for the top thread and a bobbin for the bottom

- thread, means for passing the bobbin through a loop of the needle thread, a take-up device for the top thread for pulling the stitch tight, and a thread lock for holding 5 the top thread between the supply and take-up, the take-up device operating to measure thread after the needle has carried a loop of thread through the work, said take-up device having a fixed length of 10 movement for measuring thread while the loop of thread is being held by the needle in the work at a fixed distance from the end of the stitch regardless of the length of stitch or thickness of the work.
- 15 12. A sewing machine having a needle for the top thread and a bobbin for the bottom thread, means for passing the bobbin through a loop of the needle thread, a take-up device for pulling the stitch tight, and a 20 thread lock for holding the top thread between the supply and take-up device, the take-up device operating to measure thread after the needle has carried a loop of thread through the work, said take-up device having a fixed length of movement for measuring 25 thread while the loop of thread is being held by the needle at a fixed distance from the end of the stitch regardless of the length of stitch or thickness of the work, and a tension adjustment for said thread lock whereby the amount of thread measured by said 30 take-up device may be regulated.
13. A sewing machine having a work table adapted to support the work right side up, 35 an eye-pointed needle for the top thread arranged to operate from above said work table, a shuttle mechanism operating below the work table, and a take-up device operating on said top thread above the work table 40 for feeding the top thread and for setting the stitch, said take-up device operating while the needle is stationary at a fixed distance below the work table to pull a length of thread from the supply equal to that required for the stitch.
14. A sewing machine having a work table adapted to support the work right side up, an eye-pointed needle for the top thread arranged to operate from above said work table, a shuttle mechanism operating below the work table, and a take-up device operating on said top thread above the work table for feeding the top thread and for setting the stitch, said take-up device operating while
- the needle is stationary at a fixed distance 55 below the work table to pull thread from the supply, and an adjustable tension device for maintaining a predetermined amount of tension in the top thread during the thread feeding operation of the take-up device and 60 for locking said thread during the stitch setting operation of said take-up device whereby the tightness of the top thread after the stitch is set is controlled.
15. A lock stitch sewing machine having 65 a work table adapted to support the work right side up, an eye-pointed needle for the top thread arranged to operate from above said work table, a looper mechanism operating below the work table, means for holding 70 the lower locking thread for passage of the needle thread loop around the same, and a take-up device operating on said top thread above the work table for feeding the top thread, said take-up device having a fixed 75 stroke and operating in conjunction with the needle and looper mechanism while the thread is being held below the work thereby to pull the required length of thread from the supply irrespective of the length of the 80 stitch and thickness of the work.
16. A wax thread sewing machine having a work table adapted to support the work right side up, an eye-pointed needle for the top thread arranged to operate from above 85 said work table, a looper mechanism operating below the work table, means for holding the lower locking thread for passage of the needle thread loop around the same, and a take-up device operating on said top thread 90 above the work table for feeding the top thread and for setting the stitch, said take-up device having a fixed stroke and operating in conjunction with the needle and looper mechanism while the thread is being 95 held below the work thereby to pull the required length of thread from the supply, and an adjustable tension device for maintaining a predetermined amount of tension 100 in the top thread during the thread feeding operation of the take-up device and for locking said thread during the stitch setting operation of said take-up device whereby the tightness of the top thread is controlled.

Signed at St. Louis, Missouri, this eighth 105 day of January, 1916.

HENRY P. SCHOENKY.
